UNITED STATES PATENT OFFICE.

WINFRED N. LURCOTT, OF WEEHAWKEN, NEW JERSEY, ASSIGNOR, BY MESNE ASSIGNMENTS, TO GRIPLOCK, INC., OF NEW YORK, N. Y., A CORPORATION OF DELAWARE.

WIRE-STRAP-SEALING MACHINE.

Application filed January 10, 1920. Serial No. 350,545.

The present invention relates particularly to machines for uniting the ends of wire straps used for securing packing cases and like articles, and more particularly for manipulating the seal disclosed in Letters Patent of the United States for improvements in wire strap seal and method of forming the same granted to me November 20, 1923, and having the Number 1,474,372, to which patent cross reference is here made.

The invention has for its object to draw the wire straps tightly upon the packing case or article being bound, and to hold the same while the seal is perfected, which, after the machine is removed, holds the strap under tension; to furnish a light and easily manipulated tool for the purpose mentioned; to adjust the movements of the power applying members in opposite or counter-effective directions; and to provide a tool for performing the functions for which it is designed rapidly.

Drawings.

Figure 1 is a side view of a tool constructed and arranged in accordance with the present invention;

Figure 2 is a plan view of the tool partly in section, the section being taken on the line 2-2 of Figure 3;

Figure 3 is a side elevation partly in section, the section being taken as on the line 3-3 in Figure 2;

Figure 4 is a vertical cross section the section being taken as on the line 4-4 in Figure 1; and

Figure 5 is an end view of the tool.

Figure 6 is a side edge view of the knot or tie formed by the helix of the wire after the same has been compressed.

As shown in the application to which reference has been made, the wire strap 9 has at one end an open spiral 8, which is coiled back and around the adjacent portion of the said strap, to form the end loop 10 and loops 12, through which the free end 13 of the wire is passed prior to the seal being closed by pressing the said loops 12 on the parallel lapped portions of the strap. To hold one end while exerting a pull on the strap the present machine employs a serrated foot 14, and a toothed dog 15. The dog 15 has a pivot 16, on which it swings so that the toothed end 17 will bite upon to hold the end of the strap 9 adjacent the spiral 8.

In placing the machine with reference to the strap, it is moved until the spiral 8 rests in a vise having a bed 18 and platen 19. In this position of the coil 8, the dog 15 is swung on its pivot 16 and the toothed end 17 bites on the strap 9. The free end 13 of the strap is then guided through the loops 10 and 12 of the spiral 8, and carried back to be inserted in one of the cross grooves 20 opening from the face of the winch head 21. When the portion of the free end 13 is so disposed in one of the grooves 20, the winch head 21 is rotated by manipulating the handle 22. The winch head 21 is rigidly mounted on a shaft 23, which extends through bearings in the machine body 24, and has rigidly mounted at the opposite end a ratchet wheel 25. The body 24 is shaped to form a boss 26, which forms a bearing for the handle 22, on which the said handle pivots. The handle 22 is furnished with a pawl 27, the tooth of which engages the teeth in the ratchet wheel 25 whenever the handle is lifted. When the handle 22 is depressed, the pawl 27 rides over the teeth of the wheel 25.

When the free end 13 has been adjusted in engaging relation to the winch head 21, the handle 22 is successively lifted to rotate the wheel 25, and the winch head 21 connected therewith. This action of the winch head 21 bends the free end 13 of the strap around the winch head and draws the strap tightly upon the box.

During the strain imparted to the strap the end having the spiral 8 is held against movement by the dog 15 and the foot plate 14. To assist in exerting the necessary heavy strain on the strap 9, the operator holds the machine in level position by grasping with one hand the handle 29 of the lever 30, while with the other hand he grasps the hand hold 31, set out from the side of the handle 22.

As the wheel 25 is turned, a pawl 32 engages the wheel 25, to prevent the retrogression thereof during the returns of the handle 22 for renewing the grips of the ratchet wheel 25.

By reference to Figures 3, 4 and 5, it will be seen that the free end 13 of the strap is adjacent the outer edge of the bed 18, and in the path of a cutter which grips that portion of the free end 13 adjacent and inside of

the spiral 8 as the said spiral is closed and pressure applied on the platen 19. The severed portion of the free end 13 is that which has been wound on the winch head 21, and 5 which after being severed by the cutter 33 is readily and quickly removed from the said winch head.

The platen 19 is moved by the lever 30 toward the bed 18 to flatten or mash the coil 10 8 so that the sections thereof displace upward and downward the portions of the strap contained within the coil.

To this end the platen 19 is mounted in a guide frame 34, which is normally suspended or lifted away from the bed 18 by 15 a suspension spring 35. The platen 19 is depressed toward the bed 18 by crank pins 36, which are formed in shafts 37, being preferably machined therefrom and eccentric thereto. The crank pins 36 are engaged by links 38. The links 38 are paired and are of equal length and engage at their lower ends bearing shafts 39, which extend 20 between the sides of the platen 19.

25 In their operation the shafts 37 are rotated in relatively reverse directions, due to the fact that they are operatively connected by gear wheels 40 and 41. By reason of this construction the pins 36 move toward each other when pressure is being applied through the links 38 to the platen 19. Canting or rocking of the platen during the moment of pressure is thereby avoided.

The shafts 37 are rotated by the gears 35 and 41. Power is primarily applied to the gear wheel 41 by the lever 30. The lever 30 is forked and has bearings on one of the shafts 37. Between the members of the fork is pivoted a dog 43. The dog 43, as best seen 40 in Figure 1 of the drawings, has teeth to engage the teeth of the gear wheel 41, and is pivoted on a shaft 44, extending between the sides of the fork 42. By means of this construction when the lever 30 is lifted, the dog 43 runs freely back over the wheel 41, the teeth of said dog engaging the teeth of said wheel whenever the movement of the lever 30 is arrested to depress the handle end 29 thereof.

50 By this arrangement a relatively large movement of the handle 25 in relation to the shafts 37 is obtained, and is multiplied by the number of the movements described. In practice the lever 30 is raised and lowered a number of times during the half rotation of the shafts 37, which depresses the platen 19 sufficient to flatten the spiral 8 and clamp the ends of the strap 9 held thereon. During each recession of the lever 30 to obtain 55 a new grip on the wheel 41, the dog 45 engages and holds the wheel 41 against return. The pawl 45 is lifted into engagement by a flat coil spring which is held within a barrel socket 45* surrounding the pivot on which the said pawl is mounted.

It will be seen that when the shafts 37 have completed a half revolution the pins 36 pass the vertical center between the shafts 39 and the center of the shafts 37. The pressure imposed upon the platen at this time, 70 and the pull of the spring 35, tend now to lift the pins 36. In this movement the shafts 37 and parts connected therewith are released, the dogs 43 and 45 permitting the wheel 41 to rotate freely. The result of this 75 is that automatically the machine, after having performed its work, raises the platen 19, to permit the removal of the machine from the strap without further operation on the part of the attendant.

80 From the foregoing it will be seen that when using the machine such as described, the wire strap may be quickly adjusted and drawn to the proper tension, preparatory to applying pressure to the seal for locking 85 the same. It will also be seen that after the tension has been obtained, the pressure for locking the seal may be quickly applied and automatically, as soon as the locking 90 of the seal has been completed, the operating parts of the machine are quickly and automatically opened, ready to remove the machine from the seal, to be employed in forming another seal.

95 It will be understood that various changes may be resorted to in the form, construction and arrangement of the several parts, without departing from the spirit and scope of my invention; hence I do not intend to be limited to the details herein shown and described except as they are included in the 100 claims.

Claims:

1. A machine as characterized comprising a vise; means for holding a looped end of a wire strap in said vise, means engaging the opposite end of said strap to draw the same through said looped end within said vise, and means for closing said vise on said looped end to crimp said opposite end over 110 the sides of said looped end.

2. A machine for sealing wire straps which are provided at one end thereof with an open wound helix, said helix enveloping the opposite end of said strap, said machine comprising a vise, means for holding the helix between the jaws of said vise, said means embodying a gripping device for engaging said strap adjacent said helix, and means engaging the opposite end of said strap after the same 115 has been passed through said helix for drawing the same therethrough to tighten said strap upon an object to which said strap is being applied.

3. A machine for sealing wire straps which are provided at one end thereof with an open wound helix, said helix enveloping the opposite end of said strap, said machine comprising a vise, means for holding the helix between the jaws of said vise, said means em- 120

bodying a gripping device for engaging said strap adjacent said helix, and means engaging the opposite end of said strap after the same has been passed through said helix for drawing the same therethrough to tighten said strap upon an object which said strap is being applied, said means embodying a rotary winch member having a head provided with a snubbing device for holding said free end while the same is drawn taut.

4. A machine for sealing wire straps which are provided at one end thereof with an open wound helix, said helix enveloping the opposite end of said strap, said machine comprising a vise, means for holding said helix between the jaws of said vise, said means embodying a gripping device for engaging said strap at a point adjacent said helix, means engaging the opposite end of said strap after the same has passed through said helix for drawing the same therethrough to tighten said strap upon an object to which said strap is being applied, said means embodying a rotary winch member having a head provided with a snubbing device for holding said free end while the same is drawn taut, and means for closing said vise on said loop after the free end of said straps are tightened.

5. A machine for sealing wire straps which are provided at one end thereof with an open wound helix, said helix enveloping the opposite end of said strap, said machine comprising a vise, means for holding said helix between the jaws of said vise, said means embodying a gripping member for engaging the wire carrying said helix adjacent said helix, means embodying a rotary winch adapted to engage the free end of said strap after being drawn through said helix, and power means for rotating said winch after engagement with said strap, and means for closing said vise to compress the convolutions of said helix to crimp the portions of said strap encompassed therein.

6. A machine for sealing wire straps which are provided at one end thereof with an open wound helix, said helix enveloping the opposite end of said strap, said machine comprising a vise, means for holding the helix between the jaws of said vise, said

means embodying a gripping device for engaging said strap adjacent said helix, means engaging the opposite end of said strap after the same has been passed through said helix for drawing the same therethrough to tighten said strap upon an object to which said strap is being applied, means for closing said vise to compress the convolutions of said helix to crimp the portions of said strap encompassed therein, and means for severing said opposite end of the strap substantially simultaneously with the closing of the vise.

7. A tool for uniting the ends of wire straps, each having at one end thereof an open helix, said helix providing an open passage therethrough for the opposite end of said strap, said tool comprising, means for tensioning said strap and means for crushing said helix while the strap is under tension for uniting the ends thereof.

8. A tool for uniting the ends of wire straps, each having at one end thereof an open helix, said helix providing an open passage therethrough for the opposite end of said strap, said tool comprising, means for tensioning said strap, means for crushing said helix while the strap is under tension for uniting the ends thereof and means for severing said opposite end of the strap.

9. A tool for uniting the ends of wire straps, each having at one end thereof an open helix, said helix providing an open passage therethrough for the opposite end of said strap, said tool comprising, means for gripping one end of the strap, means for pulling on the other end of the strap for tensioning the strap, and means for crushing said helix while the strap is under tension for uniting the ends thereof.

10. A tool for uniting the ends of wire straps, each having at one end thereof an open helix, said helix providing an open passage therethrough for the opposite end of said strap, said tool comprising, means for tensioning said strap, means for crushing said helix while the strap is under tension for uniting the ends thereof, means for severing said opposite end of the strap, and common actuating mechanism for the crushing and severing means.

WINFRED N. LURCOTT.
